(57) **CLAIM**

I claim the ornamental design for a speaker system, as shown and described.

DESCRIPTION

FIG. 1 is a perspective view of an embodiment of a speaker system;

FIG. 2 is a different angle perspective view of the speaker system from FIG. 1;

FIG. 3 is a front view of the speaker system FIG. 1;

FIG. 4 is a back view of the speaker system from FIG. 1;

FIG. 5 is a right side view of the speaker system from FIG. 1;

FIG. 6 is a left side view of the speaker system from FIG. 1;

FIG. 7 is a top view of the speaker system from FIG. 1;

FIG. 8 is a bottom view of the speaker system from FIG. 1;

FIG. 9 is a perspective view of another embodiment of the speaker system in accordance with the present disclosure;

FIG. 10 is a different angle perspective view of the speaker system from FIG. 9;

FIG. 11 is a front view of the speaker system FIG. 9;

FIG. 12 is a back view of the speaker system from FIG. 9;

FIG. 13 is a right side view of the speaker system from FIG. 9;

FIG. 14 is a left side view of the speaker system from FIG. 9;

FIG. 15 is a top view of the speaker system from FIG. 9;

FIG. 16 is a bottom view of the speaker system from FIG. 9;

FIG. 17 is a perspective view of another embodiment of the speaker system in accordance with the present disclosure;

FIG. 18 is a different angle perspective view of the speaker system from FIG. 17;

FIG. 19 is a front view of the speaker system FIG. 17;

FIG. 20 is a back view of the speaker system from FIG. 17;

FIG. 21 is a right side view of the speaker system from FIG. 17;

FIG. 22 is a left side view of the speaker system from FIG. 17;

FIG. 23 is a top view of the speaker system from FIG. 17; and,

FIG. 24 is a bottom view of the speaker system from FIG. 17.

The features shown in broken lines in the various Figures are for illustrating environmental structure and form no part of the claimed design.

1 Claim, 21 Drawing Sheets
